COSMETIC HOLDER

Giles C. Fullmer, Bridgeport, Conn., assignor to
 The Bridgeport Metal Goods Manufacturing
 Company, Bridgeport, Conn., a corporation of
 Connecticut

Application October 31, 1934, Serial No. 750,801

8 Claims. (Cl. 206—56)

This invention relates to new and useful improvements in cosmetic holders, and relates particularly to cosmetic holders of the type especially designed to hold lipsticks, eyebrow pencils and 5 the like.

An object of the invention is to provide a cosmetic holder of neat and attractive appearance, which is easy to operate, and is of simple and inexpensive construction whereby it may be 10 manufactured at low cost.

Other objects and advantages will become apparent from a consideration of the following detailed description taken in connection with the accompanying drawings wherein satisfactory 15 embodiments of the invention are shown. However, it will be understood that the invention is not limited to the details disclosed, but includes all such variations and modifications as fall within the spirit of the invention and the scope of the appended claims.

In the drawings:

Fig. 1 is a vertical sectional view through the holder with the cover thereof in closed position;

Fig. 2 is a somewhat similar view but with the cover withdrawn and the lipstick fully projected;

Fig. 3 is a longitudinal sectional view taken substantially along the line 3—3 of Fig. 1;

Fig. 4 is a transverse sectional view taken substantially along the line 4—4 of Fig. 1;

Fig. 5 is a side elevational view of the holder, with parts broken away and showing the cover as it begins to open or close;

Fig. 6 is a top plan view of the holder with the cover closed;

Fig. 7 is a side elevational view showing the operating parts and carrier removed from the casing;

Fig. 8 is a side elevational view showing the upper portion of a side wall of the casing;

Fig. 9 is an enlarged detail sectional view through an upper corner portion of the casing and showing in section the cover mounting and the means for operating the cover;

Fig. 10 is an enlarged detail sectional view through a portion of the cover mounting, the view being taken at right angles to Fig. 9;

Fig. 11 is a view similar to Fig. 1 but showing a modified construction;

Fig. 12 is a vertical sectional view of the holder of Fig. 11 but with the lipstick projected for use;

Fig. 13 is a vertical sectional view taken substantially along the line 13—13 of Fig. 11;

Fig. 14 is a transverse sectional view taken substantially along the line 14—14 of Fig. 11;

Fig. 15 is a view partly in side elevation and partly in section and showing the relative location of the parts of the modified construction as the cover begins to open or close;

Fig. 16 is a top plan view of the modified holder 5 with the cover closed;

Fig. 17 is a side elevational view of the operating parts of the modified construction removed from the casing;

Fig. 18 is a view partly in elevation and partly 10 in section showing the upper portion of the modified holder with the cover omitted;

Fig. 19 is a view partly in top plan and partly 15 in section showing the modified construction of carrier;

Fig. 20 is an enlarged sectional view through an upper corner portion of the casing of the holder of Fig. 11 and showing the cover mounting and operating means.

Fig. 21 is a side elevational view of the lower 20 portion of an inner shell employed in the modified construction;

Fig. 22 is a view at right angles to Fig. 21; and

Fig. 23 is a view looking from the underside in 25 Fig. 22.

Referring in detail to the drawings, and at first particularly to Figs. 1 through 10, the improved cosmetic holder as illustrated includes an outer elongated transversely rectangular sheet metal casing 10 closed at its lower end as by wall 11 and having its upper end open as at 12. In

its side wall 13 the casing 10 is provided with a relatively long slot 14 closed at both ends but extending longitudinally of the casing. The opposite side walls 15 and 16 of the casing have 30 panel-like portions 17 and 18 pressed inwardly thereof, and the vertical edges 20 of said panels within the casing form a guideway 21 at the inner side of the slotted wall 13 of the casing.

The opposite vertical edges, designated 22, of 35 40 the panels 17 and 18 are spaced from the side wall 23 of the casing and form a vertical guideway 24 while the lower edges of said panel, designated 25, are spaced from the bottom wall 11 of the casing providing a guideway or passage 26. 45

The upper inner surfaces or edges 27 of the panels 17 and 18 form abutments for a cover as will later appear.

Within the casing in the guideway 21 there is arranged a slide 28 forming a support for the 50 cover 40 and the finger operator 32. The support may, as best shown in Fig. 9, include pieces 29 and 30 welded together as at 31 and of which the piece 30 extends above the piece 29. Its lower end may be bent inwardly to form a flange 30a 55

against one end of member 28. I am not, however, confined to this construction. An operating member or thumb piece 32 is arranged against the casing wall 13 and includes a shank 33 extending through the slot 14 of said wall and headed over or screw threaded or otherwise connected with or secured to the slide 28. A flexible element 34 is secured to the slide 28 by solder or other suitable means, and this flexible element as shown comprises a length of flat spring metal secured at one end to the slide 28 and having its opposite end portion secured as by means of a rivet 35 or the like to a cosmetic carrier 36 adapted to receive the inner or lower end of a lipstick or other cosmetic 37. The flexible element 34 may be of other suitable material.

It will be noted that the slide or support 28 being rigidly connected to the flexible element 34 is really a part of it, and therefore the cover 40 and thumb piece 32 are connected to the flexible element and this flexible element may be the support for the cover and the thumb piece, or the cover and thumb piece may be secured directly to the flexible element.

25 The carrier 36 has its upper end open to receive the inner or lower end of the cosmetic 37. When the carrier is in its innermost position as shown in Fig. 1 the flexible element 34 extends downwardly through the guideway 21 and through the passage or guideway 26, where the flexible element is curved, and thence upwardly in the guideway 24 where the end of the flexible element is secured to the carrier by the rivet 35. The wall 38 of the carrier through which the rivet 35 passes is of greater width than the body portion of the carrier which fits between the panels 17 and 18, and the side walls of the carrier are enlarged or spread laterally as at 39, adjacent the wall 38 and these enlarged rib-like portions 40 overlie the vertical edges 22 of the panels 17 and 18 of the casing 10, as shown in Fig. 4, whereby movement of the carrier in the casing is guided.

A rigid metal cover 40 normally closes the open end 12 of the casing, and when this cover is in closed position it may rest on the upper edge portions 27 of the panels 17 and 18. The cover is hingedly connected with the slide 28 and for this purpose the upper edge of the portion 30 of the slide is provided with a pair of extensions curled to provide eyes 41 and 42. The cover 40 is provided at one edge with extensions curved to provide eyes 43 and 44. When the eyes of the cover are brought into registry with the eyes on the slide portion 30 a pair of bars 45 are passed through all of such eyes. As will later be more fully understood it is not essential that two of the bars 45 be used since a greater or lesser number, if desired, will serve very well.

Thereafter the cover is moved downwardly to an inclined position as shown by the full lines in Fig. 7 where the cover is not at right angles to the slide portion 30 but is below the horizontal position it would occupy if it were at right angles to said slide portion. Next, by any suitable means the eye 41 of the extension 30 is pinched or has pressure applied thereto to depress a portion of the eye into one of the bars 45 as at 46 and to press a corresponding portion of said bar into the other bar as at 47. It will be understood that this operation locks the bars 45 to the eye 41 of the slide portion 30. Either before or after the eye 41 is locked to the bar 45 as described the eye 44 of the cover is similarly treated as indicated at 48 whereby such portion of the latter eye is forced into one of the bars 45 and a corre-

sponding portion of said bar is forced into the other bar as at 49 and the cover is locked to the bar.

When the bars 45 are secured to one of the eyes of the slide portion 30 as above described and then to an eye of the cover as above described it will be appreciated that movement of the cover from the full line position of Fig. 7 to either dotted line position of that figure must result in a twisting of the bars 45. Since this is true the normal position of the cover with respect to the slide 28 is shown by the full lines in Fig. 7 and there is a constant effort to return the cover to this position when moved therefrom. The arrangement is such that when the stud 33 of the button or finger piece 32 is at the upper end of the slot 14 the hinge connection between the cover and the slide 28 is so located that the cover is resting on the upper edges 21 of the panels 17 and 18 of the casing 10 and the cover is in a horizontal position closing the open end of the casing. With the cover in this position the bars 45 are somewhat twisted and are constantly tending to return to normal position and incline the cover below horizontal position so that the cover is tightly held in closed position.

When the cover is in closed position, the carrier 36 is in its innermost position and the cosmetic 37 is fully within the casing and is enclosed and protected. To expose the cosmetic for use, the operating member or finger piece 32 is forced downwardly or in a direction toward the lower end of the slot 14 and as the operating member moves the slide 28 moves with it. This slide is movable in the guideway 21 above described as being at the inner side of the slotted wall 13 of the casing. As the slide moves inwardly away from the open end of the casing it draws the cover 40 with it, and as the hinged end of the cover attempts to move downwardly into the guideway 21 the undersurface of the cover rides against the corner portions 50 represented by the junctures of the vertical edges 20 and the top edges 27 of the panels 17 and 18 of the casing and the cover is forced open as suggested in Fig. 5.

From Fig. 5 it will be noted that the cover is forced open on initial inward movement of the slide 28 so that the cover is out of the way and is exposing the open end of the casing for movement of the cosmetic 37 through such end of the casing. Further movement of the slide inwardly of the casing from the position of Fig. 5 results in further swinging movement of the cover toward open position and finally results in the cover being drawn into the guideway 21 within the casing where it is out of sight and protected against injury. As the slide is moved as stated it exerts a pushing force on the flexible element 34 so that the element is pushed downwardly or inwardly with respect to the guideway 21 and upwardly or outwardly with respect to the guideway 24. Therefore, this inward movement of the slide 28 results in the carrier 36 and the cosmetic 37 being moved toward the open end of the casing, and sufficient movement of the slide results not only in the cover 40 being drawn into the casing but also in the cosmetic being projected outwardly through the open end of the casing for use. The limit of movement of the parts is defined by the inner end of the slot 14 in the casing wall and the parts are shown at the limit of their movement in Fig. 2.

Of course, it is not necessary to project the entire cosmetic when the latter is new since it is but necessary to project its outer end beyond

the casing for use. It will, therefore, be clear that the operating member 32 need not be shifted from the outer to the inner end of the slot 14 except after the cosmetic is worn or has been used to such an extent as to materially reduce its length, and it will also be clear that by maintaining a thumb on the operating member 32 the user will not force the cosmetic back into the casing by the pressure used in applying the cosmetic.

To withdraw the cosmetic into the casing it is but necessary to shift the operating member toward the upper or outer end of the slot 14. As this is done the flexible element 34 is drawn 15 downwardly in the guideway 24 and upwardly in the guideway 21 and the cover is moved out through the open end in the guideway 21, and due to the torsional mounting of the cover it springs into place fully closing the end 12 of the 20 casing when the hinge connection of the cover, with the slide 28, reaches the outer end of the guideway 21. As shown best in Fig. 4 the flexible element 34 is of a width equal to the widths of the guideways 21 and 24 and due to the bowing 25 of said member at the lower end of the casing or through the passage 26 the end portions of said member are constantly pressing flat against the inner surfaces of the casing walls 13 and 23 as shown in Figs. 1 and 2 and when the cover 40 is 30 closed the slot 14 in the casing wall is closed by the portion of the element 34 pressing against said wall of the casing.

Referring now to Figs. 11 through 23, the holder includes an outer casing 51 corresponding 35 in all respects with the casing 10 of the figures first described except that the side panels are not pressed inwardly, and within the casing 51 is an inner shell 52 open at its upper end and having its lower end closed by a curved wall 53. This inner shell 52 is secured in place within 40 the casing as by pressing a portion 54 of the outer casing through a wall of the inner shell as best shown in Fig. 18. The wall 55 of the casing 51 is provided with a longitudinally extending slot 56 and the inner shell is so arranged within 45 the casing 51 as to leave a guideway 57 between such inner shell and the slotted wall 55 of the casing.

A short flange 58 spaces the upper portion 50 of the inner shell from the wall 59 of the casing 51 and a lug 60 on said inner shell assists the flange 58 in maintaining a passageway 61 between the casing wall 59 and the adjacent wall 62 of the inner shell. This adjacent wall of the inner shell is provided with a longitudinally extending slot 63 the purpose of which will later be fully 55 set forth.

The lug 60 above referred to is, as clearly 60 shown in Fig. 22, formed by lancing and pressing a portion from a wall of the inner shell and a downwardly extending lug 64 on said inner shell is formed by lancing a portion from the curved bottom wall 53 of the shell and pressing such lanced portion downwardly. When the shell is 65 within the casing this lug 64 engages the bottom wall of the casing as shown and may be of assistance in locating the shell in the casing prior to the fastening of the shell in place by pressing the portion 54 of the casing through the shell, 70 and it will be noted that the curved bottom wall 53 of the inner shell is held spaced from the bottom wall 65 of the outer casing.

With the described construction it will be noted that the guideway 57 is connected with the guideway 61 by a passage 66 representing the space

between the bottom wall 53 of the inner shell and the bottom wall 65 of the outer casing. Within the guideway 57 is one of the slides 28 previously described, and secured to said slide in the manner previously described is the cover 40. 5 The hand piece or operating member 32 has its shank 33 extending through the slot 56 in the casing wall 55 and secured to the slide 28 so that said slide may be moved along the guideway 57 by manipulation of the operating member 32 in 10 a direction to carry its shank along the slot 56.

A flexible element 67 corresponding with the element 34 of the figures first described is arranged in the casing 51 at the outer side of the inner shell 52 and passes about the lower curved 15 wall of the inner shell having its end portions disposed in the guideways 57 and 61. That end portion of the flexible element located in the guideway 57 is secured to the slide 28 in any suitable manner as by solder or the like and the 20 other end portion of said flexible element is secured to a carrier 68 located within the inner shell as by means of a rivet or stud 69 passing through the slot 63 in the wall 62 of the shell.

While the carrier 68 will later be described in 25 detail it is here noted that said carrier receives the lower end of a lipstick or other cosmetic 70. It will be understood that the slide 28 is movable longitudinally along the guideway 57 by proper manipulation of the operating member 32 and 30 since said slide is connected with the carrier 68 it will be clear that movement of the slide inwardly away from the open end of the casing 51 will result in movement of the carrier toward 35 the open end of the casing, and that return movement of the carrier will result in movement of the carrier away from the open end of the casing. That is, the slide may be shifted from the position of Fig. 11 to that of Fig. 12 and the carrier will be shifted from the position of Fig. 11, where 40 the cosmetic is within the casing, to the position of Fig. 12 where the cosmetic is exposed for use.

The carrier 68 is a double carrier and includes 45 an outer shell 71 which is transversely rectangular to conform with the shape of the shell 52 and this outer shell is open at its lower end but at its upper end is provided with a wall 72 having a circular opening 73 therethrough. A transversely circular shell 74 is arranged within the shell 71 50 and is of a diameter having a snug fit therein and is substantially concentric with the opening 73 through the wall 72 of the shell 71. As here disclosed, this transversely circular shell 74 receives the lower end of the cosmetic 70 which end 55 extends through the opening 73 in the shell 71.

Since the shell 74 is of the shape of the cosmetic 70 it properly receives the lower end of the latter and as the shell 74 has a snug or forced fit in the shell 71 the cosmetic is held against 60 turning movement relative to said latter shell. Shell 71 being of the shape of the shell 52 the carrier 68 will be properly guided in its movements by said shell 52. When the cosmetic stick or pencil is transversely rectangular the transversely circular shell 74 of the carrier may be omitted and the shell 71 of the carrier may be reversed so as to dispose its open end uppermost to receive the inner end of such cosmetic.

It will now be understood that normally the 70 cosmetic 70 is wholly within the casing 51 and that the open end of the latter is closed by the cover 40 all as shown in Fig. 11. From this figure it will also be noted that the slot 56 in the wall 55 of the outer casing is substantially closed by 75

- one arm or end portion of the flexible element 67. Therefore, the cosmetic 70 is fully enclosed and is protected from powder or tobacco crumbs or the like and is further protected from crushing.
- 5 When the cosmetic is to be used, the operator shifts the operating member or button 32 inwardly from the open end of the casing and this results in a corresponding movement of the slide 28. As the slide moves the cover 40 must move 10 with it since these parts are hinged together, and as the hinged connection moves into the passageway 57 the underside of the cover 40 engages the upper edge portion 75 of one wall of the inner shell 52 and is forced open against the action of 15 the torsion springs 45 to the position of Fig. 15. Also, as the slide 28 moves inwardly of the guideway 57 it acts through the flexible element 67 to move the carrier 68 outwardly or toward the open end of the casing. It will be noted in 20 Fig. 15 that the cover 40 is swung back from closed position during initial movement of the slide 28 so that the cover is out of the way before the cosmetic reaches the open end of the casing. Fig. 12 shows the parts at the end of their extreme movement and there it will be noted that the cosmetic is fully projected. However, it is not necessary to move the parts to the limit of their movements except when the cosmetic is worn down after repeated use.
- 25 Particularly by reference to Fig. 13 it will be noted that the lug 64 at the inner end of the inner shell 52 is located at one edge of the flexible element 67 so as to guide said element in its movement through the passageway 66 connecting the guideways 57 and 61 at the inner side of the bottom wall 53 of the shell 52. As the slide 28 is moved outwardly from the position of Fig. 12 the springs 45 of the hinge connection between the slide and cover will immediately move the cover to 40 closed position as in Fig. 11 when the hinged connection between the cover and slide reaches the outer end of the guideway 61.
- It will now be understood that the panels 17 and 18 pressed inwardly from the side walls of 45 the casing 10 of Figs. 1 through 10 form the guideways in which the slide 28 and the flexible element 67 operate, and it will further be clear that said panels serve to guide the carrier 36 in its movement. The upper edges of the panels 50 form stops against which the cover 40 bears when in closed position and the corner portions 50 of the panels serve to force the cover open as in Fig. 5 when the hinged connection of the cover with the slide 28 moves into the passageway 21.
- 55 In Figs. 11 through 23 panels are not pressed from the side walls of the casing 51 but the inner liner 52 replaces the panels.
- Having thus set forth the nature of my invention, what I claim is:
- 60 1. In a cosmetic holder, a casing having an open end and a longitudinal slot in a side wall, a carrier in the casing and movable toward and from the open end thereof, a support in the casing, a thumb piece exterior of the casing and connected to the support through the slot to shift the support in a direction longitudinally of the casing, a flexible resilient strip connecting the support and carrier and normally closing the slot, said strip being arranged so that on movement of the support in a direction away from the open end of the casing the carrier is moved toward said open end, a cover normally closing the open end of the casing, means hinging the cover to the support for swinging movement outwardly 75 away from the open end of the casing and for

sliding movement along a wall of the casing with the support as the latter is operated to move the carrier toward the open end of the casing, and spring means to swing the cover across the opening when the support is returned to normal position.

2. In a cosmetic holder, an elongated transversely rectangular casing open at one end and having a pair of panel portions pressed inwardly from opposite walls with the edges of said panel portions spaced from the other opposite side walls of the casing and defining therewith guideways, a carrier in the casing between said panels and having a pair of lateral portions extending into one of said guideways, a support in the other guideway, a flexible element connected at one end with said support and extending downwardly therefrom and across the casing and upwardly in the other guideway, means connecting the other end portion of said flexible element with the carrier, and means to shift said support in said guideway and operable through said flexible element to move said carrier toward and from the open end of the casing.

3. In a cosmetic holder, an elongated transversely rectangular casing open at one end and having a pair of panel portions pressed inwardly from opposite walls with the edges of said panel portions spaced from the other opposite side walls of the casing and defining therewith guideways, a carrier in the casing between said panels, a support in one of said guideways, a flexible element connected at one end with said support and extending downwardly therefrom and across the casing and upwardly in the other guideway, means connecting the other end portion of said flexible element with the carrier, means to shift said support in said guideway and operable through said flexible element to move said carrier toward and from the open end of the casing, a cover normally closing the open end of the casing, and means hinging an edge of the cover to the support whereby as the latter is shifted to move the carrier toward the open end of the casing the cover is drawn into the guideway with the support.

4. In a cosmetic holder, an elongated transversely rectangular casing open at one end and having a pair of panel portions pressed inwardly from opposite walls with the edges of said panel portions spaced from the other opposite side walls of the casing and defining therewith guideways, a carrier in the casing between said panels, a support in one of said other opposite side walls of the casing, said casing wall having a slot therein, a flexible element connected at one end with said support and extending downwardly therefrom and across the casing and upwardly in the other guideway, means connecting the other end portion of said flexible element with the carrier, and means extending through said slot and connected for operation to shift said support in said guideway and operable through said flexible element to move said carrier toward and from the open end of the casing.

5. In a cosmetic holder, a casing having an open end and the opposite end closed by a flat transverse wall, a carrier in the casing movable longitudinally thereof, said casing having a longitudinal slot in a side wall, a support slidably longitudinally of the casing, manual means operable from the exterior of the casing and connected to said support through the slot to shift the support, a flexible resilient band connected

adjacent one end to the support and adjacent the other end to the carrier for shifting the carrier and normally closing the slot in the casing, said band being curved upon itself at the closed 5 end of the casing, a curved guide means for the band at the concave side thereof, a rigid cover normally closing the open end of the casing and hinged to the support to swing outwardly away from said open end, spring means tending to 10 move the cover to closing position, said cover being drawn into the casing on movement of the support away from the open end thereof, and means for swinging the cover about its pivot outwardly away from the end of the casing as it 15 is drawn into the casing.

6. In a cosmetic holder, a casing having an open end, a carrier in the casing and movable toward and from the open end thereof, a support slidable along one side wall of the casing, 20 a thumb piece exterior of the casing and connected to the support to move the support toward and from the open end of the casing, a flexible resilient band forming a connection between the support and carrier whereby as the support is 25 moved in a direction away from the open end of the casing the carrier is moved toward the open end of the casing, a cover hinged at one edge to the support to swing outwardly away from the open end of the casing and normally crossing 30 the open end of the casing, said cover being movable by the support to a position at a side wall of the casing as the support is operated to move the carrier toward the open end of the casing, and spring means at the hinge to swing 35 the cover to closing position over said open end as the support is returned to normal position.

7. In a cosmetic holder, a casing having an open end, a carrier in the casing and movable toward and from the open end thereof, a support 40 slidable along one side wall of the casing, a thumb piece carried by the support at the exterior of the casing to move the support toward and from the open end of the casing, a flexible resilient band forming a connection between the

support and carrier whereby as the support is moved in a direction away from the open end of the casing the carrier is moved toward the open end of the casing, a cover hinged at one edge to the upper edge of the support to swing outwardly away from the open end of the casing and normally crossing the open end of the casing, said cover movable by the support into a position at one side of the casing as the support is operated to move the carrier toward the open 10 end of the casing, means engaged by the cover on its initial movement with the support to swing the cover on its hinge to carry it away from its position crossing the open end of the casing, and spring means to swing the cover to closing position 15 over said open end as the support is returned to normal position.

8. A cosmetic holder comprising a casing having an open end, a shell within the casing having an open end adjacent that of the casing, a 20 carrier in the shell and movable toward and from the open end thereof, a support slidable along one side wall of the casing, a thumb piece exterior of the casing to move the support toward and from the open end of the casing, a flexible 25 resilient band forming a connection between the support and carrier whereby as the support is moved in a direction away from the open end of the casing the carrier is moved toward said open end, said shell having spacing lugs at one side 30 between its inner end portion and the casing to space the shell from the casing to provide a guide space for the flexible band, a cover hinged to the support to swing outwardly away from the open end of the casing and normally closing said 35 open end, said cover being movable by the support to a position on a side wall of the casing as the support is operated to move the carrier toward the open end of the casing, and means to swing the cover to closing position over said 40 open end as the support is returned to normal position.

GILES C. FULLMER.
